UNITED STATES PATENT OFFICE.

JAMES A. HINSON, OF CHICAGO, ILLINOIS.

BUFFING DEVICE FOR RAILWAY-CARS.

SPECIFICATION forming part of Letters Patent No. 663,273, dated December 4, 1900.

Application filed February 6, 1900. Serial No. 4,244. (No model.)

To all whom it may concern:

Be it known that I, JAMES A. HINSON, a citizen of the United States, residing at Chicago, in the county of Cook and State of Illinois, 5 have invented certain new and useful Improvements in Buffing Devices for Railroad-Cars; and I do declare the following to be a full, clear, and exact description of the invention, such as will enable others skilled in the art to 10 to which it appertains to make and use the same.

This invention relates to buffing devices for railroad-cars, and has for its object to provide a simple device of few parts adapted to maintain the buffer-plates of adjacent cars in 15 contact throughout their lengths at all times, both in buffing and pulling, and particularly in rounding curves, and to take up lost motion between the cars; and it consists of the parts and combination of parts hereinafter 20 described and claimed.

In the accompanying drawings, forming a part of this specification, Figure 1 is a plan view of a platform-frame and draft and longitudinal sills of a car, having the flooring 25 broken away to show my invention in position; Fig. 2, a longitudinal vertical section on line X X, Fig. 1; Fig. 3, a front elevation of the platform with the buffer-plate removed and the metal face-plate partly broken; Fig. 30 4, a transverse vertical section on line Y Y, Fig. 2; and Fig. 5, a detail perspective of the buffer-plate.

Similar letters refer to similar parts throughout all the views.

Referring to the drawings, A represents a car-platform, and B a buffer-plate arranged across the end of the platform and in line with end sill C of the car, and D a horizontal top plate secured to and resting on a flange a, 35 formed on the plate B and abutting against a vertical projection or flange b, formed by rabbeting the edge of said plate B. This construction serves to strengthen the buffer-plate and prevent its bending from the blows received in buffing, especially when it is brought 40 in contact with narrow buffer-heads, such as the type known as the "Miller" buffer-head. The plate D extends into a recess or space formed in the upper surface of the end timber F of the car-platform and works below a 45 foot-plate E, secured to said end timber. The buffer-plate B is further strengthened by a

rearwardly-projecting flat rib c, formed thereon at right angles and adapted to enter a narrow elongated slot d, formed in the front 55 face of the end timber F of the platform when the buffer-plate is driven back in buffing. The rib c, as best shown in Fig. 5, is widest at its middle portion and gradually reduces toward its ends, where perforated lugs 60 e are formed for the attachment of the guide- rods G to the buffer-plate. The guide-rods are preferably forked at their ends to embrace the lugs e and are pivotally secured thereto by countersunk rivets, whereby said buffer-plate 65 may have a free yielding movement in a horizontal plane at each end. Across the face of the end timber F is secured, preferably by screws, a metal plate H, in which is formed an elongated opening f, corresponding to the slot 70 d in the end timber F, and terminating in square openings g at each end of said opening f. Through openings g and openings in the end timber F the guide-rods G extend back to and through openings in the ends of the arms h h' 75 of the yoke I, where they are secured by pins or keys i. The rear portions of the rods G are reduced and rounded, so as to provide a shoulder j, against which or a loose collar k thereon one end of the spiral springs K, which surround said rods, abuts, the other end of the springs bearing against a collar l, loosely arranged on the rods and formed with a diametrically-extending rib m, which fits in a 80 recess or groove n, formed across the face of the ends of the arms h h' of the yoke. The yoke comprises the arms h h', jointed or hinged together at their meeting ends by a pin o, which also serves to connect a bar J to the yoke for a purpose to be described. The 85 arms h h' are flattened and curve from their inner ends to their outer ends, as shown in Fig. 1, and are widened at their inner ends both for the purpose of strengthening the same and to form the projecting jaws L, having 90 the short bosses p formed on their adjacent faces in advance of the pivotal point of the arms. The bosses serve to retain a spring M 95 in position between the jaws.

As shown in Fig. 1, the arm h is formed circularly and perforated, as at v, to enter between the lugs or ears w of arm h' and with shoulders w' to engage the stops y on the arm h', and thus limit the movement of the arms 100

on the pin o . The arms $h h'$ are formed on the curved lines shown, so as to present the convex bearing-surface w^2 , Fig. 1, and the concave bearing-surface w^3 .

5 The yoke-arms extend through narrow elongated openings r , formed in the draft-timbers N , and work on combined wear and stop plates P , secured by bolts in the said openings r . The plates P are turned up vertically 10 at their rear ends, as at s , to bear against the end sill of the car and are formed with a raised rib t , curved to correspond to the curve of the arms $h h'$, and with a rounded projection u , which forms a fulcrum for the said arms when 15 in action. The ribs t extend from the ends s of the plates P to the projections u and laterally from the latter.

The bar J is formed with a forked end, so 20 as to embrace the jointed or hinged ends of the arms, and is secured thereto by the pin o and extends back to the end of the draw-bar, to which it is bolted or otherwise firmly secured.

25 The car-coupler proper may be of any desired type or form and is connected in the usual or any desired manner with the follower-plates and draft-springs.

With the parts in the position shown in 30 Fig. 1 any pull or forward movement of the coupler draws the yoke I bodily forward against the pressure of the springs K owing to its connection therewith through the rod J , so that in starting a train of cars the buffer-plates of adjacent cars are kept firmly together 35 and in direct contact and closing the space which would otherwise be left between them. When the cars are brought together in buffering, the buffer-plates are driven back and the side-springs K compressed. The coupler being also driven back at the same time causes the bar or rod J to draw back the center pivotal point of the yoke I , thus throwing the outer ends of the arms $h h'$ forward and compressing the spring M and taking up 40 lost motion and reducing the movement of the plate B . Owing to the fact that the movements of the yoke-arms are limited by the shoulders w' on the arm h engaging the stop y on arm h' the yoke will be bodily moved 45

forward by the bar J when the coupler is pulled forward, and that buffering on the coupler causes the bar J to draw the inner jointed ends of the arms $h h'$ backward, which causes the outer ends of the said arms to be thrown forward, because of their bearing on the rounded projections u of the stop and wearing plates P , which act as fulcrums, thus holding the buffer-plates in contact and preventing lost motion between the plates.

Having thus described my invention, what 60 I claim as new, and desire to secure by Letters Patent, is—

1. In a buffering device for railroad-cars, a jointed yoke, jaws projecting from one side of the joint of said yoke, a spring arranged 65 between said jaws, a buffering-plate connected to the free ends of said yoke, a rod connecting the center of said yoke and the draw-bar of a coupler, means for throwing the free ends of the yoke forward when the center of 70 the yoke is drawn back, and means for causing the yoke to move bodily forward when the center of the yoke is pulled forward.

2. In a buffering device for railway-cars, a platform end sill having an elongated slot or 75 opening therein, a plate having a corresponding opening terminating in enlarged openings at each end secured to said end sill, a buffering-plate having a rib adapted to enter the elongated opening in the sill, a yoke, and guide-rods connecting said yoke and buffering-plate.

3. In a buffering device for railway-cars, a yoke comprising two arms hinged together at one end, one of said arms being formed with shoulders and the other with a stop to engage 85 said shoulders to limit the movement of the arms, jaws projecting from said arms, a spring between said jaws, a buffering-plate, means for connecting said yoke and buffering-plate, and a bar connecting the hinged ends 90 of said arms to the draw-bar of a coupler.

In testimony whereof I affix my signature in presence of two witnesses.

JAMES A. HINSON.
